UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

MEANS FOR OPERATING VAPOR ELECTRIC LAMPS.

No. 894,766.

Specification of Letters Patent. Patented July 28, 1908.

Application filed December 26, 1902. Serial No. 136,552.

To all whom it may concern:

Be it known that I, EZECHIEL WEINTRAUB, a subject of the Czar of Russia, residing at Schenectady, county of Schenectady, State 5 of New York, have invented certain new and useful Improvements in Means for Operating Electric Vapor-Lamps, of which the following is a specification.

My invention relates to the operation of 10 electric lamps in which the current flows through the medium of a vapor such for example as the vapor of mercury, and comprises certain improvements whereby a plurality of lamps of this character may be operated in series with each other, either in a constant current circuit, or from a source of current of constant potential.

In carrying out my invention in practice I 20 provide means whereby all of the lamps may be connected in circuit and whereby the lamps may start independently of each other.

Features of novelty which characterize my invention are pointed out with particularity in the appended claims while the invention 25 itself, both as to the arrangement of apparatus and mode of operation, is set forth in detail in the following description which is to be taken in connection with the accompanying drawings which represent one of the various 30 embodiments which my invention may assume.

The type of lamp which I employ is one in which the starting of the lamp is secured by means of a supplementary electrode between 35 which and one of the main electrodes a small arc is initiated thereby serving to start up the main discharge or arc between the main electrodes. Three lamps of this type are shown in the drawings but it is to be understood 40 that any number of lamps may be operated, limited only in number by the power of the supply circuit. In the drawings the lamps shown are duplicates of each other so that it will be necessary only to describe one 45 of the lamps in detail.

The lamp shown at the top of the drawings consists of a tube 1 of indefinite length, this tube being arranged in a slightly inclined position, though the particular position chosen 50 is not important. At one end of the tube is a main electrode 2 formed of soft steel, artificial graphite, or other suitable material, or the electrode may be of mercury, and this electrode is connected through a platinum or

other suitable leading-in wire 3 with the external terminal 4 of the lamp. The other main electrode of the lamp is formed by a body of mercury 5 which fills a hollow depending extension 6 of the tube 1, through the walls of which extension extends a platinum leading-in wire 7 constituting the other external main terminal of the lamp. Adjacent to the depending extension 6 is another downward extension 8 filled with a body of mercury 9 up to such a level that the mercury bridges 65 over the space between the two extensions 6 and 8 as indicated at 10. Floating in this body of mercury 9 is a small closed glass tube 11 closely surrounding a rod 12 of iron or other magnetic material constituting an armature or core for a solenoid 13 which is arranged about an upward extension 14 of the tube so as to surround the upper portion of the core or armature. This core or armature slides within a guiding tube 15 affixed to 75 the upper portion of the extension 14.

A leading-in wire 16 makes contact with a body of mercury 9 and is connected to one terminal of the solenoid 13, the other terminal of which is connected to the first of a pair 80 of contacts 17 and 18, the latter being connected to one of the leads of the supply circuit. The main terminal 4 of the lamp 1 is also connected to the supply lead but indirectly through the winding 19 of a solenoid 85 the core 20 of which is adapted to carry a bridging contact 21 for making and breaking electrical connection between said contacts 17 and 18.

The other lamps shown in the drawings are 90 the same in construction as that already described so that no detailed description thereof is necessary. These lamps 22 and 23 are connected with each other and to the lamp 1 by means of connections extending in 95 the case of the lamp 1 from the main electrode 7, which in this case is a cathode, to one terminal of the solenoid 24 constituting a portion of the cut-out for the lamp 22, the other end of this solenoid being connected to 100 the positive electrode or anode 25 of the lamp 22. In a similar manner the negative or cathode 26 of the lamp 22 is connected to the solenoid 27 of the remaining lamp 23, the other terminal of the solenoid being connected to 105 the positive terminal 28 of the lamp 23. The cathode terminal 29 of this lamp is connected to a switch 30 by opening

or closing which current may be supplied from the mains 31 or interrupted as desired.

The position of the parts as shown in the drawings indicates the condition of affairs 5 when no current is flowing. If now the circuit be closed current flows from the mains down through the by-pass or starting circuit including the cut-out contacts 17, 18, the starting solenoid 13, and the resistance 35, to 10 supplementary terminal 16 and then through the body of mercury in the lamp and out from the main terminal 7 to the contacts 32 of the cut-out magnet 24 of the next lamp 22. Current then flows to the starting solenoid 33 and so on through the lamp in the same manner as through the lamp 1, the circuit being continued through the lamp 23 in the same manner as through the preceding lamp. The effect of the resulting flow of 15 current is to energize the starting solenoids such as 13 and 33 of the lamps, thereby drawing up the corresponding armatures such as 12 in lamp 1. As the armature in each lamp is drawn up, the level of the mercury 9 falls due to the decreased displacement of the tube 11 surrounding the solenoid core. The body of mercury 10 which forms the connecting link between the bodies of 20 mercury 5 and 9 then separates thereby interrupting the circuit so as to form an arc or electric discharge. The ionized mercury vapor set free by this discharge operates by reason of the migration of its ions to set up an electric discharge between the main terminals 2 and 5 of the lamp whereupon the lamp is brought into normal operation, current flowing through the solenoid 19 of the cut-out to the main terminal 4 of the lamp. The cut-out then operates to disconnect the 25 starting solenoid 13 from the circuit thereby interrupting the flow of current through the side branch formed by the supplemental electrode 9 co-operating with the body of mercury 5 forming one of the main electrodes of the lamp. In the same manner as soon as current is started in the side branches of the other lamps in circuit thereby starting these lamps into operation, the cut-outs corresponding thereto operate to interrupt the 30 supplemental arcs produced in the side branches of the lamps for the purpose of starting the same.

In the drawings I have represented a series of vapor lamps as being supplied with current from a constant potential source indicated conventionally by the constant potential mains 31. Under these circumstances a resistance is inserted in the main circuit at 34 in order to limit the current to a given value 35 and to make the arcs more stable. In addition, resistances 35—36 and 37 are connected in the side branches of the respective lamps as indicated to prevent excessive flow of current. When the lamps are supplied from a 40 source of current of constant value the necessary

sity for the resistances no longer exists and they may be omitted.

I do not claim in this application the individual lamp or vapor electric device, but

What I do claim as new and desire to secure 70 by Letters Patent of the United States is,—

1. The combination of a plurality of vapor electric lamps, connections interlinking said lamps in series with each other, means for impressing upon the lamp circuit an electromotive force of a value sufficient to maintain the lamps in normal operation, a temporary starting circuit in shunt to each lamp, and means responsive to the starting of each lamp for cutting out the 75 corresponding starting circuit.

2. The combination of a plurality of vapor electric lamps, connections interlinking said lamps in series with each other, means for impressing upon the lamp circuit an electromotive force of a value sufficient to maintain the lamps in normal operation, a temporary starting circuit in shunt to each lamp, and electro-magnetic means responsive to the starting of each lamp for cutting 80 out the corresponding starting circuit.

3. The combination of a plurality of vapor electric lamps, connections interlinking said lamps in series with each other, a resistance in shunt to each lamp, and a cut-out responsive to flow of current in the lamp for interrupting the circuit of said resistance. 85

4. The combination of a series of vapor electric lamps, a constant potential source of current supply therefor, a resistance in shunt to each lamp, a cut-out having its contacts in the circuit of the resistance and its energizing coil in circuit with the lamp, and current limiting means permanently in series with the circuit of said lamps. 90

5. The combination of a plurality of vapor electric lamps, connections interlinking the electrodes of the lamps in series with each other, a resistance in shunt to each lamp, means for causing current to flow between 95 said electrodes, and means responsive to said current for interrupting the circuit of said resistance. 100

6. The combination of a plurality of vapor electric devices, connections interlinking said devices in series with each other, a starting circuit in shunt to each of said devices, means controlled by said starting circuit for initiating a flow of current between the working electrodes of said lamp, and means responsive 110 to said current for de-energizing the starting circuit. 115

7. The combination of a source of constant potential current, a circuit in shunt to said source including vapor electric devices in 120 series, means for simultaneously producing an auxiliary starting arc or discharge in each device, and means responsive to the starting of said device for interrupting the auxiliary 125 or starting arc.

8. The combination of a plurality of vapor electric devices, connections interlinking said devices in series with each other, a bypass circuit about each of said devices, means 5 for interrupting each of said circuits when the corresponding vapor electric device starts, and a device having resistance permanently in series with said vapor electric devices.
10. The combination of a plurality of vapor electric devices, a device having resistance connected permanently in series therewith, connections interlinking said devices in series with each other; a circuit containing resistance 15 in shunt to each of said devices, and means for opening the shunt circuits con-

taining resistance when the corresponding vapor electric devices start.

10. The combination of constant potential mains, a circuit in shunt to said mains 20 including vapor electric devices in series, a starting circuit for each of said devices, and a cut-out for each starting circuit, the contacts of the cut-out being located in the starting circuit and the energizing coils in the circuit of corresponding vapor electric devices. 25

In witness whereof, I have hereunto set my hand this 24th day of December, 1902.

EZECHIEL WEINTRAUB.
